PULVERIZING MACHINE

Henry G. Lykken, Minneapolis, Minn.

Application November 13, 1936, Serial No. 110,732

17 Claims. (Cl. 83—11)

The present invention relates to machines for reducing particle size, or pulverizing materials, of the type wherein the reduction in size is accomplished in the dry state, and further to the classification of the pulverized materials, and to the processes of reduction in size and of classification whereby material of a predetermined size may be delivered from said machine.

In the present machine the energy imparted to the air or other gaseous media, such as steam, carbon dioxide, nitrogen, hydrogen or mixtures of these and other gaseous fluids, constitutes the force for moving the particles of material upon each other to cause the reduction in size by this attrition action, as well as to provide the reducing atmosphere. In addition reduction in size is caused by the erosion of the particles by the high speed moving air or gas, and the gaseous media, including air, may be heated or refrigerated depending upon the materials to be reduced. For convenience in the following specification this method of reduction will be referred to as air attrition and the reduction in size will be referred to as pulverization, but this is to be understood as not limiting the definition of the actual conditions.

The machine of this application is useful for the reduction of material even to very small particle size, and the classification and separation of the pulverized material for either coarse or fine sizes, i. e., from ten mesh screen size on the one hand to one micron size on the other hand.

Furthermore, the machine of this application is effective in the reduction or pulverization of materials normally classified as friable, as well as those that are normally classified as non-friable. Talc, which is an example of a friable material, and iron chips and turnings, which is an example of elastic, non-friable materials, have been successfully reduced in particle size or pulverized, and to substantially the same fine particle.

Air attrition has heretofore been successfully embodied in so-called pulverizing or reducing apparatus, as shown for example in my Patents 45 Numbers 1,753,437 issued April 8, 1930, 1,756,253 and 1,756,254 issued April 29, 1930. These are cited as examples of types of machines.

In Patents Nos. 1,753,437 and 1,756,253 a high speed rotor is used to produce high velocity, substantially unidirectional, circulating air currents creating what will be termed a vortex about the axis of the rotor. In such a vortex the air currents necessarily travel at different rates of speed. This occurs in a closed chamber into

which is fed the material to be pulverized. The particles of material fed into the machine are carried about in the air currents and become part of the vortex, and are thus caused to contact with and rub upon each other, producing an abrading action resulting in the reduction in particle size or pulverization.

When the material is reduced to the desired degree of fineness in those machines, the material laden air rises from the pulverization zone and ultimately reaches a place of collection or use. While the centrifugal force of the vortex action referred to causes a classification of the materials due to the differences in mass of the 10 different particle sizes of materials in the pulverizing zone, in the machine of Patent No. 1,753,437 there is a further classifier of pulverized material interposed ahead of the place of collection or use and into which the material laden air passes. In this latter chamber any over-size material is separated from that of the desired size, the over-size returning to the pulverizing zone and the correctly sized material passing from the machine.

In the machine of Patent No. 1,756,254 the same character of vortex action is set up to effect air attrition, but by the use of high pressure air ejected through tangential nozzles, the material being reduced and classified in the one 15 casing, and the material of proper particle size being removed from the center of the chamber.

The machine of the present invention is an improvement upon the aforementioned machines in the method and the apparatus of pulverization, as will be more fully pointed out hereinafter. There is also provided in this machine a new and improved classifier which may be used either in conjunction with machines of my former patents or of the present invention, or 20 of other types, or separately as a classifier in any case where it is desired to classify materials pneumatically.

One of the objects of the present invention is to provide a new method of securing reduction in particle size of materials in a dry state.

Among other objects of my invention are to provide a machine in which there are major and minor attrition vortices; in which there is an outer vortex and a plurality of inner vortices; in 25 which there are vortices of different speeds, or of different radii having different centers of rotation; in which coarser grinding is done in one vortex and finer grinding is done in another vortex fed from the first vortex; and in which there is a rapidly moving annulus of material laden air

in which aided by centrifugal force the particles mull upon each other to reduce themselves, and within the annulus are a plurality of smaller whirling masses in which there is a more intense mulling of the particles upon themselves.

It is another object of my invention to provide a new method of classifying materials in a dry state through the use of a gaseous medium.

Other objects of my invention are to provide a classifier in which the material progresses through a chamber in a substantially linear direction moving upwardly in a volute manner, and in which no disturbing air or eddy currents are created.

Still further objects of my invention are to provide a classifier in which means are present to cause classification due to frictional skin-core effects; in which the size of particle discharged from the classifier is a function of the height of the classifier; which will select material of small particle size, as fine as one micron in size; and a classifier which may be used with any pulverized material or pulverizer.

Still another object of my invention is to provide a machine for effecting reduction in particle size of either or both friable and non-friable materials to substantially equal degree.

A further object of my invention is to provide a machine in which within reasonable limits materials of different specific gravity may be simultaneously reduced and classified and removed from the machine without disturbing the proportions of the materials as fed into the machine. (As a matter of fact the machine of this invention will more thoroughly mix and uniformly distribute the various components of the mixture passing through the same so that the delivered material is improved in this respect over the material fed into the machine.)

A further object of my invention is to provide a machine for accomplishing the aforementioned objects wherein the apparatus comprises one unit.

Still further objects of my invention are to provide a machine for accomplishing the aforementioned objects in an efficient and economical manner as to both space and power consumption; and a compact machine of simple construction and of few parts and freedom from wear, which machine is adaptable to easy assembly and replacement of parts, and rapid and thorough cleaning.

It is a further object of my invention to provide a machine in which reduction of particle size is obtained for all practical purposes without contamination of the materials composing the machine.

Even further objects of my invention are to provide an arrangement for feeding a uniform amount of material into the reducing chamber and to control the feed of air into the machine; to remove from the machine materials of substantially uniform particle size; to provide a classifier in which the particle size of the material delivered from the machine is readily and easily controllable; and to provide an economical method of grinding to a definite particle size by promptly removing from the reducing zone material which has attained the desired particle size.

Other and further objects and advantages of my invention will be understood from the following specification taken in conjunction with the accompanying drawings, wherein—

Figure 1 is a vertical cross sectional view of a device constructed in accordance with my invention;

Fig. 2 is a horizontal cross sectional view taken in the plane of line 2—2 of Fig. 1;

Fig. 3 is a horizontal cross sectional view taken in the plane of line 3—3 of Fig. 1;

Fig. 4 is a diagrammatic illustration of a formula for the spacing of the rotor blades according to my invention.

Fig. 5 is a diagrammatic illustration of a portion of a rotor and showing another method of calculating blade spacings according to the present invention; and

Fig. 6 is a diagrammatic illustration of a portion of the classifier showing the classifier action.

The machine of the present invention comprises a cylindrical casing mounted on a hollow base and carrying on top of the casing a hollow discharge chamber. Extending through the cylinder is a shaft connected to a motor mounted outside the casing. On the shaft adjacent the base is a rotor and extending upwardly from the rotor adjacent the top of the machine is a smooth cylinder or drum which is also mounted on the shaft. Both the rotor and the drum are of smaller diameter than the casing, leaving annular zones therebetween. The lower part or that zone opposite the rotor is the attrition or pulverizing zone and the upper part, opposite the drum, is the classifier zone.

Material to be reduced is continuously fed into the attrition zone from a hopper, the feed being at a uniform rate to maintain efficient balanced operating conditions in the machine in which it is neither underloaded nor overloaded. In one embodiment of a machine for continuous production, air, or other gaseous media, is introduced into the machine from the hollow base through an appropriate annular opening at the bottom edge of the rotor. In either case, the air inlet is adjustable to control the volume of air admitted, which is one of the factors controlling the particle size of the finished product.

The rotor consists of a plurality of vertical blades equally spaced about the rotor. The air is caused to whirl uni-directionally about the rotor axis by the force created by the blades of the high speed rotor. As the material is fed into the attrition zone, it is picked up in this current of air and whirled about the chamber, the material being carried by the air. Very soon there will be an annulus of material laden air in this zone and, due to centrifugal forces, the material in the annulus will segregate itself with the finer particles adjacent the rotor and the coarser, larger particles adjacent the casing. The layers of material will necessarily move at different rates of speeds because of the different distances thereof from the axis of the rotor and this will of itself produce a mulling of the particles upon each other and bring about attrition or abrading or reducing action.

Ordinarily, between each pair of rotor blades there is, in effect, a closed end depression or pocket which may be closed at the bottom without communication with adjoining pockets or may be opened at the bottom so that all pockets communicate with each other. Air is drawn into each pocket by the partial vacuum formed at the back of the forward or leading blade and air is forced out along the front side of the trailing blades so that there is merely a flowing in and out movement of the air in each pocket. This air movement is merely incidental to the rotation of the rotor and serves no useful purpose.

I have discovered that with the proper spacing between the outer edge of the rotor and the wall of the casing, and the proper spacing of the rotor blades with respect to each other, there will be produced a large number of small, substantially closed circuit, individual vortices, respectively formed between each pair of opposing blade faces and extending partially into the inner surface of the outer vortex, which vortices very materially aid and speed up the attrition action, and allow of obtaining reduction of all of the material to very fine particle sizes, even to one micron size or lower, and in substantial volume. It is not altogether certain, but I believe that the coarser grinding takes place in the outer or larger annulus or vortex, while only the finer particles are picked up in the inner, smaller, higher speed vortices, and that the intense mulling action occurring in these smaller vortices produces the very finely ground material which I have been able to obtain in machines constructed according to my invention. By reason of the high rotative speed of the rotor, causing proportionately high speeds of both the outer and inner vortices, there occur an innumerable number of collisions of the particles moving at these very high speeds, which materially aids in the reduction of particle size, as will be now fully explained.

The material ground to the predetermined size being entrained in the air currents rises from the attrition zone into the classification zone. I have discovered that by controlling the amount of air introduced into the machine, there is carried from the attrition zone not only the particular particle size desired but also some material of larger particle sizes. However, this action promptly and quickly removes from the attrition zone substantially all that material which has already attained the desired particle size, and that results in the following advantages: The finished material is maintained a somewhat uniform desired size substantially free of particles smaller than that size; there is a substantial saving of power because the finely pulverized material is removed from the mass of material yet to be ground; and the further attrition action of the larger and heavier particles is not cushioned by the presence of the smaller particles, all so that active work of reducing particle size goes forward continuously, efficiently and economically. These results are further aided by the removal continuously of the fine material (mostly of intermediate over-size) from the outer vortex by the inner vortices, and the latter promptly giving up that material which is reduced in size.

The classifying zone is desirably of such a height that the finer particles of the selected size can be removed from the top of the classifying zone, and the larger particles fall by gravity back to the attrition zone to be there further reduced.

In the classifying zone, the vortex motion of the material laden air entering the classifier is maintained above that level at which such vortex of itself would be effective. This vortex movement is maintained by the rotation of the smooth, imperforate-walled drum which is mounted coaxially with the rotor. Because this drum is imperforate and has no outwardly extending projections there is no agitation or beating of the dust-laden air, and the movement of the material laden air is maintained only sufficiently to accomplish classification without fur-

ther attrition. There is, however, not sufficient force in the whirling air in the classifier zone to support the heavier and larger particles, and hence under the action of gravity they return to the reducing zone. That is, due to the frictional losses and the energy expended in maintaining the vortex action, the air progressively loses its velocity as it ascends in the classifier chamber to the discharge opening, and during this progressive reduction in air velocity the larger particles drop out, progressively as to their size, as the gravitational force overcomes the vortex influence upon the particles. Accordingly, the height of the classifier is determined by the desired particle size of the material to be delivered from the machine.

The outlet chamber is provided with a fan which discharges the classified material radially from the machine to the place of collection or use.

The fact that material as small as one micron in size can be successfully produced and successfully classified in and delivered commercially from apparatus constructed according to my invention shows the efficacy of the methods of and apparatus for pulverization and classification.

Referring to the drawings, and more particularly to Figs. 1, 2 and 3, the machine comprises a hollow base 10, two superimposed cylinders 12 and 14, a discharge casing 16, and a cover plate 18. The material to be reduced in size is fed into the machine by the feeding mechanism indicated generally at 20, is reduced or pulverized by my new method in the lower chamber defined by the cylinder 12, is classified by my new method in the upper chamber, defined by the cylinder 14, enters the discharge chamber 16, and is removed from the machine through the discharge outlet 22. Air, used in the pulverizing and classifying operations in the indicated embodiment, is admitted into the hollow base 10 through the air-inlet opening 24 and enters the pulverizing or attrition chamber 12 through the annular air-seal opening 26.

The machine is provided with a central shaft 28 which extends from the top to the bottom of the machine and is mounted in a lower bearing 30 and an upper bearing 32, which bearings may be of any desired construction to accomplish their intended purposes. The shaft 28 is shown directly connected to the motor 34 for rotating the same, but it will be understood that the shaft may be driven through speed reduction or speed multiplication mechanisms, such as gearings, pulleys, etc.

The attrition chamber 12 has a rotor mounted on the shaft 28, comprising upper and lower spider frames 36 and 38 respectively having central hubs 40 and 42 and outer cylindrical walls 37 and 39. It will be understood that it is not essential to have the rotor divided into sections, also that the rotor may comprise more than two sections, and may be constructed in a variety of forms. Secured to the bottom of the frame 38 is an annular plate 44, mounted between the frames 36 and 38 is an annular plate 46, and upon the top of the frame 36 is another annular plate 48, all of which terminate a fixed distance from the surrounding wall 12. The frames and plates are secured together by a multiplicity of bolts 50, only one of which is shown for clarity of the illustration.

Mounted between the plates of the rotor and spaced equal distances therearound are a plurality of fan blades 52, which may be of any suitable

construction. One construction of removable blade which I have found to be satisfactory is to provide a tube 54 to the outside of which is welded a cylindrical rod 56. The tubes 54 of the upper and lower rotor sections are aligned with appropriate openings in the several rotor plates and a pin 58 is passed therethrough, as shown in Fig. 1. Each of the pins 58 has a tube 60 secured to the projecting upper end thereof which tubes screw into appropriate openings in the upper plate 62, to be hereinafter more fully referred to. The upper ends of the tube 60 are exposed from above the plate 62 and have fastened therein a block 64 that is internally screw-threaded as shown. When it is desired to remove the rotor blades for cleaning, or for replacement, an appropriate screw-threaded tool is inserted into the block 64, to unscrew the tube from the plate 62, the insertion being made through opening 66, which is covered by cap 68 bolted to cover plate 18. The tube 60 and attached pin 58 is removed through opening 66, thus making it possible to lift out the rotor blades through a side door 10 provided in the wall of the chamber 12. One or more doors 10 may be provided to permit ready cleaning of the attrition chamber 12.

It will be noted that the fan blades 52 are spaced from the interior of the outer wall of the attrition chamber 12 and that they are also spaced from the walls 31 and 39 of the center frames, although this latter spacing is not essential.

Air, as stated above, enters the machine through the opening 24 in the hollow base 10, which opening is surrounded by a collar 72 that is slotted to receive a gate 74 adapted to be appropriately adjusted and set to regulate the size of the air intake opening and thereby control the amount of air admitted to the machine. This control is of importance in connection with determining the degree of fineness of the finished product and also permits of variations in accordance with the mass or the specific gravity of the material being ground. In instances where the reduction in size is accomplished in atmosphere other than air, as is sometimes done, this regulation of the amount of the gaseous medium entering the machine becomes important from other angles, such as eliminating wasting of the gases, and other advantages readily perceived by those skilled in the art.

On the interior of the base and arranged on a level above the air inlet opening 24 is an annular plate 76, supported upon brackets 78, through the central opening of which the air is drawn by a plurality of air-impellers 80 riveted to the underside of the lower rotor plate 44. These impellers 80 are equally spaced about the plate 44 and direct the air into the air-seal 26 formed by a flat ring 82 extending inwardly a sufficient distance to overlie the projecting edge of the lower rotor plate 44 and yet spaced a short distance above the top thereof, thus providing a narrow passage for the entrance of air into the attrition chamber at high velocity to prevent material being forced out through this opening during the operation of the rotor, and also preventing the air from entering the grinding chamber in a direct path. The ring 82 has a vertical flange 84 bolted to the interior of the outer wall of the attrition chamber 12 by bolts 83, the holes for which are enlarged to permit adjustment of the air-seal ring 82, and are covered by plate 85 fitting under the bolt head. The bars 56 of the fan blades are recessed as shown at 86 to provide

clearance for the ring 82 if necessary, and also to avoid setting up forceful currents to interfere with the current of incoming air.

However, should any of the material fall below the ring 82, as for example if the machine should be overloaded or if the machine should be shut down before all of the material in the attrition chamber was reduced and had passed out of the machine, such material would accumulate on top of the plate 76, will be carried around by the pressure of the air impellers 80 until the material reaches opening 90 when the material will drop into the pocket 88 provided at one side of the base 10. Material in the pocket may be removed from the machine through the side door 92.

The material to be reduced is fed into the attrition chamber from a hopper indicated generally at 94 as communicating with a feed tube 96 which registers with a feed opening 98 in the outer wall of the attrition chamber 12. A feed screw 100 rotates in the tube 96 and is driven by a worm wheel 102 mounted on the shaft 104 of the feed screw. The shaft is mounted in bearing plates 106 and 108, which are respectively of a size to close the end of the feed tube 96 and to enclose the worm wheel. The worm wheel 102 is driven by a worm 110 mounted on the shaft of a driving motor 112. As will be understood in this art, the rotation of the feed screw 100 will positively feed the material into the attrition chamber at a steady and definite rate of speed depending entirely upon the speed of the motor 112 which may be controlled in any desired manner. The feed opening 98 is shown as located near the top of the attrition chamber 12, but in some instances it may be desirable to locate this feed opening at a lower level, or even at the bottom of the attrition chamber.

When the machine is started in operation the rotor is brought up to speed and through the action of the air impellers 80 air is introduced into the attrition chamber. The rotor blades 52 take up the air and whirl it around the attrition chamber, setting up a vortex beyond the tips of the rotor blades, which will be hereinafter referred to as the outer vortex, and indicated by the heavy arrows in Fig. 2. The feeding of the material through the feed opening 98 is begun. That material is picked up in the whirling air in the attrition chamber and caused to circulate around the same, the material being entrained and conveyed in the air currents. The particles of material entering the machine are picked up by this outer vortex and generally are of comparatively large mass and weight. The centrifugal action of the whirling mass of particles and air will cause the larger and heavier particles to be carried around on the outer surface of, and the lighter particles on the inner surface of, this vortex.

The action occurring in this outer vortex may be explained as follows: All the while mulling action, due to the inertia of the particle in the air moving at high speed in the vortex, is continuing and the particle size is being reduced. As the individual particle is reduced in size the influence of centrifugal force thereon becomes less and the particles move in toward the rotor fan blades. Also in its travels, the particle is constantly eroded by the high speed air currents and reduced in size by collision with other particles in its paths. Thus the particles have three paths, one, a somewhat circular path, a second path substantially in the plane of its circular

motion and at right angles toward the center of the machine as it is reduced in size, and a third path as a result of the component of these two forces and the aspiration of the material due to the rising air currents entering through the air seal 28. The resultant of all these forces is a slowly rising spiral movement of the particle through the attrition zone. It may be pointed out that the centrifugal pressure in the outer vortex is sufficient to overcome the action of gravity. The friction of the mass of air and material against the inner surface of the outer wall of the attrition chamber will retard and practically stop the speed of rotation of the air and material at that point and thus cause a slowly traveling layer of material at the outer surface of the vortex. In some cases it may be desirable to line the inner wall of the attrition chamber 12 with a plurality of rods 14, or the wall may be provided with some other form of corrugated liner. The presence of these rods or the corrugated liner will cause the accumulation of a layer of material with very little fluid movement at this outer surface of the vortex, but either using a corrugated surface or a plain surface there will be a slowly moving layer of material and air adjacent the outer wall of the chamber past which other layers of material and air are moving. The referred to retardation of the outer surface of the outer vortex is reflected progressively inwardly through the vortex toward the inner surface thereof, while the innermost surface is traveling at substantially the peripheral speed of the rotor. These differences in speed contribute to the mulling of the particles upon each other and the causing of collision between particles to speed up the further reduction of the mass of the particles.

The rotor of the described machine operates at a high peripheral speed of the order of, for example, 150 miles per hour, although lower and higher speeds are entirely successful.

I have discovered that by properly spacing the rotor blades 52 vortices will be set up between the blades, which will be termed inner vortices. These inner vortices are formed in the following manner: The forward travel of each blade creates a vacuum immediately behind the blade. There is an immediate in-rush of air to fill the vacuum. That air is taken in part from the inner edge of the outer vortex and such air is laden with finely pulverized material. Air to fill the vacuum is also partly obtained from about the tip of the blade which air slips from in front of the blade and around its tip. The following blade, advancing toward the vacuum, compresses the air directly in front of it and this air also rushes in to fill the vacuum at very high speed due to its increased pressure. The result of these several forces will be to produce a somewhat circular high speed vorticos movement between each set of opposing faces of the fanblades.

As the particle size is reduced, greater and greater intensity of impact is required to effect further reduction. It is not practical to provide adequate peripheral velocity, sufficient for very fine grinding, as the practical mechanical and economic limit is reached at or near 300 feet per second. In these closed circuit vortices between the blades, however, velocities many times the peripheral velocity of the rotor obtain, due to the high intensity of the dual forces inducing same.

These inner vortices are inherently high speed vortices with respect to the outer vortex, and their speed is rendered even higher by reason of the

high peripheral speed of the rotor. The in-rush from the three directions noted above of material-laden air to fill the vacuum created behind each blade causes innumerable high speed impacts and collisions of the particles upon each other which, together with the pull against the inertia of the particles in the vortices and the very high speed of the vortical air currents, results in a rapid attrition of the particles to rapidly produce large quantities of very small particles, of the order of one micron and fractional micron sizes, if particles that small are desired. The inner vortices referred to are indicated by the light arrows in Fig. 2.

An effective spacing of the blades to obtain the inner vortices has been found to be according to the following formula (see Fig. 4): A line 118 is drawn on the radius running from the center of the shaft through the center of the rotor blade 52X. Then draw a line 118 tangent to the upper outside surface of the following rotor blade 52Y and at right angles to the line 118. Then draw a line 120 parallel to line 118 from the top of blade 52X at the point 122 of the intersection of the circumference and the radius of the blade. The distance between lines 118 and 120 is known as the distance "A". A distance "B" is measured along the extension of the radius line of blade 52X from the point 122 to a point 124 on the inner surface of the cylinder wall 12. (If a liner, either of the rod or a corrugated lining type is used, then point 124 is chosen as on the line intersecting the inner surface of the rods or corrugations.) A distance "C" is the spacing between the opposed faces of the blades 52X and 52Y along the dash line 128. Within the limits hereinafter noted, when the distances A plus B equal C, then the inner vortices will be set up as described above. In so far as I have yet determined with a definite maximum and minimum relationship between A and B in determining the distance "C" are: minimum, A equals 0.25 B, and maximum, A equals 0.75 B. I have found that if A plus B equals 1.3 C effective inner vortices will not be set up.

Figure 5 illustrates a section of the rotor chamber and rotor, and an alternate method of computing the spacing of the blades. The blades are shown at 52N and 52P; the individual vortices by light arrows, and the outside limiting rotor chamber wall is shown at 12 and having corrugations or rods 14 welded thereon.

In operation, a layer or concentric cylinder of material forms on the wall held in place by the centrifugal pressure of the rotating outer or uni-directional vortex. While this layer may be more or less fluid, it is slow moving and in part, stationary, due to the mass friction upon the wall and its corrugations. If the corrugations are not used there is nevertheless a film or layer of material on the wall of the cylinder, as explained above. It forms in a definite thickness, depending upon the initial clearance between the rotor and wall, the nature of the material, the rate of feed relative to the rate of reduction, and the speed of the rotor. Between this layer and the outer or uni-directional vortex zone E-E, there is a distinct slippage plane D-D. On one side of this slippage plane is a mass of more or less closely spaced particles with slow relative motion. On the other side is thinly dispersed air-suspended material in high state of agitation and vortex motion.

The arrows in each case indicate the direction of motion and flow of air. A line F-F is drawn

tangent to the inside of the concentric cylinder of material D—D. A line G—G is drawn tangent to the tip of the blade 52N and parallel to the first line. A line H—H is drawn parallel to these two lines contacting the tip of the blade 52P and perpendicular to the blade 52N.

The distance between the lines F—F and G—G is the depth of the free vortex zone. The distance between the lines G—G and H—H is the depth of the radial exposure of the blade or its effective vacuum producing surface. It is maintaining the proper relationship between these two factors that I find desirable to obtain the closed circuit effect. In this figure, the free vortex zone "E" is indicated as 2½ times the radial blade exposure "K." Again, in so far as I have determined, this ratio should not be less than 2:1—nor more than 3:1—for the maximum efficiency with a large range of materials, but I do not limit myself within such narrow margins.

If the ratio falls materially below the proper limits, a closed circuit vortex is no longer effected between the blades and merely an in-and-out movement of the air is obtained. If the ratio is materially higher, the unit vortices become small and less effective, due to the inadequate radial blade exposure.

In the event pulverizing to very fine sizes is not desired, the above spacing of the rotor blades need not be followed strictly; or if the upwardly traveling air current is so regulated that the time the material is in the attrition chamber is shortened, as when larger particle sizes are desired, the use of inner vortices will speed up the reduction to whatever size is desired.

It should be noted that the diameter of the inner vortices is such that they extend into the outer vortex so that the material therein is deposited beyond the edge of the rotor so that when the material has been sufficiently pulverized in the outer and inner vortices as described, the air laden with the sufficiently ground material will readily pass upwardly through the open top of the attrition chamber 12 directly into the classifier chamber 14.

The classifier operates on the pneumatic principle and has a rotor comprising an imperforate cylindrical shell 126 which rests upon the top plate 48 of the rotor and is welded to a ring-shaped plate 128 which is adapted to be bolted to the rotor by means of the bolts 50. Intermediate its top and bottom the shell 126 may be provided on its interior with one or more stiffening rings 130 which may be welded thereto. At its upper end the shell 126 fits into an appropriate groove on the under side of the upper plate 62, and the shell may be welded to that plate.

The shell 126 has a smooth outer surface, which may or may not be polished, and is of less diameter than the outer cylinder of the classifier chamber 14, providing an elongated classification space. The inner surface of the outer cylinder is likewise smooth, it may or may not be polished and may or may not be covered with a polished liner 132. The classification space may be of the same width as the space between the rotor blades and the outer wall of the attrition chamber, or such space may be wider or narrower than the space in the attrition chamber.

At the upper end of the classifier, which is the outlet end thereof, the space between the shell 126 and the outer cylinder wall is partially closed by a ring 134, the ring being of such a size as to leave an opening 136 between the shell 126, which passes through the opening, and the inner edge

of the ring 136. The ring 134 is shown in the present embodiment as fastened between the flange 138 of the outer cylinder of the classifier chamber 14 and the flange 140 of the discharge chamber 16 at which places the flanges are bolted together, as shown. As will be hereafter explained, it may be desirable to vary the size of the opening 136 by the use of different size rings 134, or the ring may be of a construction whereby the size of the opening 136 may be readily varied.

One or more doors 135 may be provided in the casing 14 to permit of easy examination and cleaning of the classification chamber.

It will be noted from Fig. 1 that the upper plate 62 of the classifier is located in the discharge chamber 16 and projects outwardly beyond the shell 126. On the projecting portion of the plate 62 I may provide a plurality of fan blades 142 which may be riveted or otherwise secured to the plate 62. The cover plate 62 is secured to a sleeve bushing 144 on the shaft 28.

In the operation of the classifier, the material-laden air current, already moving in a unidirectional spiral path from the attrition chamber 12, enters the classifier chamber 14 at the bottom thereof and progresses upwardly therein toward the discharge outlet 136. This air current contains the material of desired particle size with considerable material of larger particle size. It is difficult to state definitely just what the actions are that occur in the classifier, but apparently, based on theoretical considerations and my observations I believe that the following does occur.

In the classifier there are two rotating bodies, one, the rotating cylinder 126 and the other, the rotating current or vortex of material-laden air. As explained, this current of air contains particles of varying mass. As is well known, centrifugal force depends partly on mass and the centrifugal force developed will therefore tend to throw the larger and heavier particles of material to the outside of this swirling current of air, with the smaller particles at the inner surface of the vortex formed by the swirling current.

In the classifier of this application, the novel arrangement of having a rotating smooth cylinder on the inside of the vortex supplies the necessary impetus to the smaller and lighter particles of material to continue the classification thereof during the upward movement of the material-laden air by continuing the vortex action thereof until the air currents reach the discharge outlet 136. Hence with the proportions and action in the attrition chamber adjusted so that the minimum particle size produced is the particle size wanted, then with the classifier of this application, that minimum particle size can be segregated and delivered from the machine without particles of other sizes.

The moving particles are kept in suspension against the forces of gravity by the centrifugal forces and the upwardly spiralling current of air. The force of gravity is exerted downwardly and is opposed by the lift of the upwardly moving current of air, while the centrifugal force is exerted at right angles to these two forces, so that the resultant path of a particle will be along the vector line of the right angularly arranged forces. In the presence of the whirling vortex, the path of the particle is also along an upward spiral. It is obvious that in the case of a larger particle there is less lifting force and

more counteracting force due to gravity. At the same time centrifugal force is much stronger in the case of the larger particle tending to divert it to the wall of the chamber. As a result in this classification zone a larger particle will move upwardly at a slower rate than a smaller one.

As previously explained, because of the larger mass of the larger particles, those particles will be thrown to the outer surface of the moving mass of air. The inner wall of the cylinder 14 is stationary and there is considerable friction between it and the current of air passing the inner surface of this cylinder wall. This friction results in what is known as the skin-core effect, which is the progressive reduction of speed of the moving air as the air approaches this stationary surface, an effect created because the frictional engagement of the air on the inner surface of the stationary wall not only retards that air but also progressively retards the next adjacent films or currents of air toward the center of the vortex. At the very inner surface of the outer wall 14, because of this skin-core effect, the air has lost practically all of its velocity and is substantially dormant. Since centrifugal force is dependent on mass and velocity, the centrifugal force acting on the larger particles of material as they approach the inner surface of cylinder 14 slowly grows smaller and smaller until the particles reach the point where the centrifugal force does not exceed the pull of gravity, and hence these larger particles must fall. In the present construction the larger particles are returned to the attrition chamber 12. This latter action continues progressively throughout the height of the classification chamber with the larger particles being progressively smaller in size as the top of the chamber is approached.

With no turbulence in the ascending rotating column of material laden air in the classifier, for a given set of conditions of speed of rotation, volume of aspirating air, the effect of the three forces noted above, etc., the separation of the particles occurs along somewhat definite lines according to size, an indication of which is diagrammatically illustrated in Fig. 6. For particles of 100 screen mesh, for example, there is a point on the outer edge of the vortex (the wall of the cylinder 14) where centrifugal forces upon such particles, either individually or when massed together, are not sufficient to maintain the particle in suspension against the pull of gravity, and hence the particles will fall, back into the attrition chamber in the present machine. The same action occurs for particles of 200 screen mesh size and of 50 micron size, but of course the points of equilibrium of forces for these other sizes are at higher levels in the elongated classification chamber. In so far as I can now determine, I believe that the location of the point of equilibrium may be computed by considering a particle of a given size under the given set of conditions at the base of the rotating drum or cylinder 126 of the classifier, which point is designated by the letter "R" in Fig. 6. A 100 screen mesh particle will move along the path of the line R-S; a 200 mesh particle will follow the line R-S¹; a 300 mesh particle the line R-S²; a 400 mesh particle the line R-S³; a 50 micron particle the line R-S⁴, and so on progressively, with the particle of the desired size following closely the circumference

of the drum 126 and passing through the outlet 136.

The point "S" indicates approximately the point at which centrifugal pressure no longer overcomes the pull of gravity on a particle of 100 screen mesh size, the point "S" a like condition for the particle 100 screen mesh size, etc., and also the point above which the respective particles are not likely to be lifted.

Because of their smaller mass and resulting lower centrifugal effect the smaller particles move toward the inner surface of the vortex and toward the outer surface of the rotating cylinder 126. The skin-core effect also obtains at the surface of the rotating cylinder 126, but in this case, because of its high velocity it is speeding up the film of air adjacent to its surface. This contact of the material laden air with the surface of the rotating cylinder imparts energy to both the air and its contained particles of material. This added energy to the inner surface of the vortex enables the inner portion of the vortex to continue without substantial abatement for the entire height of the chamber.

It is this additional energy that is imparted to these finer particles on the inner surface of the vortex that enables them to withstand the pull of gravity throughout the length of their journey up the chamber to the discharge outlet 136. Since in the final zone of classification the larger particles have been eliminated from the interior of the vortex of moving air, as explained above, they are not lifted to the discharge outlet.

As will be seen from the foregoing there are present what appear to be two conflicting forces that apparently nevertheless contribute cumulatively to the successful operation of the classifier, namely, the slowing down of the outer surface of the vortex by the stationary wall of the cylinder 14 and the speeding up of the inner surface of the vortex by the cylinder 126.

It is to be noted that the two conflicting forces just described are not "dying" forces which dissipate themselves, but are virulent forces active throughout the length of the classifying chamber and so contribute constantly to the classification of the material passing through the chamber. The "brake" effect of the stationary wall is constantly present and the centrifugal force is constantly being augmented by the energy imparted by the rotating cylinder 126, so that both forces are at all times working toward continuous classification of material.

All conditions being equal, in the machine of this invention, the height of the classifier chamber is determined by the maximum particle size it is desired to deliver from the machine and the time needed to eliminate particles of larger sizes from the vortex in the classifier thereof. Thus, by extending the height of the classifier, particles of only the smallest size produced in the attrition chamber can be successfully segregated and delivered from the machine. On the other hand, if mixtures of particle sizes are desired, as is sometimes the case, the location of the discharge outlet 136 will be fixed at some lower level in the classifier chamber consonant with the largest of the particle sizes desired in the mixture.

When the air current enters the classifier chamber from the attrition chamber, it is heavily laden with a great mass of material, much of which is over-size. As centrifugal force acts to throw the heavier particles to the outside of the classifier, it is apparent that as the current of

material laden air progresses spirally up the classifier chamber, the larger particle sizes at the outer surface of the vortex will be progressively smaller and the amount of the volume of material suspended in the air current will be correspondingly reduced. Accordingly, in the upper regions of the classifier zone, there is a comparatively small amount of suspended material in the air stream, which allows for highly efficient final classification of the material.

The insertion of the ring 134 extending inwardly from the cylinder wall 14 acts to abruptly stop the upward travel of over-size particles which may remain in the vortex, causing them to lose their energy, and fall.

The air current, carrying the desired material, entering the outlet opening 136 is picked up by the fan blades 142 and impelled through the discharge outlet 22 of the machine, from whence it may be taken to a place of use or to a collector (not shown). It will be understood that a separate flow inducing means may be substituted for the fan 142, and need not be a part of this machine.

As an example of classifier size, I have been able to successfully classify material of less than 5 micron size in a classifier where the outer cylinder 14 is thirty-six inches in diameter and thirty-one and one-half inches high, with the rotating drum 126 concentric therewith and twenty-eight inches in diameter and with the drum rotating at a speed of 1800 R. P. M. The discharge opening 136 is one and one quarter inches in width. With other size machines it has been practical on a commercial scale to classify materials one micron in size.

While one example has been given, it is obvious that to deliver any given particle size, it is only a matter of varying the height of the classifier zone, making same high for very fine material and proportionately lower for coarser material. However, varying the quantity of air, hence its velocity, or the rotative speed of the air column, or the width of the annular space to suit requirements, also affect the fineness of the material.

With proper proportioning of the height of the classifier zone, air velocities, rotative speed and clearance, commercial classification very exactly to any desired particle size is obtainable.

As noted above, in these machines I have equally successfully reduced and classified to one micron particle size the usual friable materials as talc, colors, etc., the more difficultly friable materials as cinders and ashes, and also non-friable materials, as iron chips and turnings from lathes and milling machines.

Subject matter disclosed but not claimed in this application is being claimed in copending application of Henry G. Lykken and William H. Lykken, Serial No. 413,438, filed October 3, 1941.

While one physical embodiment of my invention has been described, it will be understood that various changes in construction could be made without departing from the principles herein outlined. Accordingly, modifications may be made in the arrangement and location of parts within the spirit and scope of my invention, and such modifications are intended to be covered by the appended claims.

I claim:

1. A machine for delivering pulverized material of predetermined sizes comprising a casing, means for supplying a gaseous medium to said machine, a rotor mounted concentrically of but

5 of less diameter than the casing for causing attrition of particles upon each other by movement of the gaseous medium in which they are suspended, a smooth cylinder mounted concentrically of but of less diameter than the casing for causing classification of the pulverized material, the spacing between the rotor and the casing and between the cylinder and the casing being substantially alike with the spaces opening into each other, and means for rotating the rotor and cylinder.

2. A machine for delivering pulverized material of predetermined sizes comprising a casing, a rotor spaced from the walls of the casing and comprising a plurality of radial, substantially imperforate blades extending longitudinally of the rotor, the blades being spaced apart a distance substantially equal to the distance between the tip of a blade and the wall of the casing plus the distance between parallel lines extending from the tips of adjacent blades when the line drawn from the tip of one blade intersects the radius of the preceding blade at right angles.

3. A machine for delivering pulverized material of predetermined sizes comprising a stationary casing, a rotor spaced from the walls of the casing and comprising a plurality of radial blades extending longitudinally of the rotor, the blades being spaced apart, according to the formula $C = A + B$ where B is the distance from the tip of the blade to the inner surface of a surrounding stationary element, where A is the distance from the tip of the blade to the point of intersection of a line drawn at right angles to the radius of the blade and touching the tip of the following blade, and C is the distance between opposing faces of the blades near the tips thereof.

4. A machine according to claim 3 wherein the distance A is not less than 0.25 B , and not greater than 0.75 B .

5. A machine according to claim 3 wherein the distance $A + B$ is not greater than 1.3 C .

6. A classifier comprising a cylindrical casing, a cylinder having a smooth wall concentric with and spaced from the casing, a rotatable shaft on which the cylinder is mounted, means for introducing a vortex of material-laden gaseous medium into the lower end of the space between the cylinder and the casing, the smooth wall cylinder acting upon the material and gaseous medium to effect classification of the material according to particle size, and a discharge outlet at the upper end of said space.

7. A classifier comprising a cylindrical casing, a cylinder having a smooth wall concentric with and spaced from the casing, a rotatable shaft on which the cylinder is mounted, means for introducing a vortex of material-laden gaseous medium into the lower end of the space between the cylinder and the casing, the material being of a variety of particle sizes, the smooth wall cylinder acting upon the material and gaseous medium to effect classification of the material according to particle size, the discharge outlet located above the lower end of said space a distance determined by the selected particle size to be classified and delivered from the machine, and a return for oversize particles.

8. A machine for pulverizing material comprising a casing, a rotor mounted therein having a projecting portion at the base thereof, means to rotate the rotor to create a vortex about the periphery of the rotor, an inlet for admitting air to the casing near the bottom of said rotor, means

for varying the size of the air inlet comprising a ring-shaped plate adjustably mounted on the casing and overlying but spaced from the projecting portion of the base of the rotor to thereby provide an air seal against the escape of material through the air inlet, and means for feeding material into said casing.

9. A machine for delivering pulverized material of selected sizes comprising a casing, a rotor of less diameter than the casing and mounted concentrically thereof, means for feeding a gaseous medium and material into the space between the rotor and the casing, the rotor causing attrition upon each other of the particles of material suspended in said medium by movement of the medium and suspended particles, an imperforate tubular element mounted concentrically of said casing and of substantially the same diameter as said rotor and arranged to receive the pulverized material in the space between the element and the casing, an outlet for the selected material, said tubular element extending substantially the entire distance between the rotor and the outlet, and means for rotating the rotor and the tubular element.

10. A machine for delivering pulverized material of predetermined sizes comprising a casing, means for supplying a gaseous medium to said machine at low pressure, a driven shaft mounted for rotation in said casing, a rotor for causing attrition of particles upon each other by movement of the gaseous medium, a hollow cylinder for causing classification of the pulverized materials, the rotor and the cylinder being mounted upon said shaft, and an outlet for the classified material located at one end of the casing, the cylinder extending from adjacent the outlet inwardly a substantial distance toward said rotor.

11. A machine for delivering pulverized material of predetermined sizes comprising a casing, means for supplying a gaseous medium to said machine, a rotor mounted concentrically of but of less diameter than the casing for causing attrition of particles upon each other by movement of the gaseous medium in the casing, means for continuously feeding material into the space between the rotor and the casing, a hollow cylindrical member mounted concentrically of but of less diameter than the casing for causing classification of the pulverized material by centrifugal action upon the material between the member and the casing, fan means for directing the gaseous medium into the space between the rotor and the casing, an outlet for classified pulverized material, the outlet being concentric with the cylindrical member, a discharge outlet from the machine, and fan means for moving the classified pulverized material through the discharge outlet, the rotor, cylindrical member and fan means being mounted co-axially.

12. A machine for delivering pulverized material of predetermined sizes comprising a casing, means for supplying a gaseous medium to said machine, a rotor mounted concentrically of but of less diameter than the casing for causing attrition of particles upon each other by movement of the gaseous medium in the casing, a smooth walled cylindrical element mounted concentrically of but of less diameter than the casing for causing classification of the pulverized material by movement of the gaseous medium in the casing, means for directing the gaseous medium into the space between the rotor and the casing, and means for operating the rotor and the cylindrical

element at substantially the same peripheral speeds.

13. A classifier comprising a cylindrical casing, an imperforate classifying cylinder mounted in said casing, the cylinder being coaxial with and spaced from the casing, means for rotating the cylinder, means for feeding material suspended in a gaseous medium directly into one end of the space between said cylinder and said casing, and a discharge outlet located adjacent the opposite end of the cylinder.

14. A classifier comprising a cylindrical casing, a cylinder having a smooth wall concentric with and spaced from the casing, a rotatable shaft on which the cylinder is mounted, means for rotating the shaft, means for feeding a suspension of material and a gaseous medium into one end of the space between the cylinder and the casing, the smooth wall cylinder acting upon the material and gaseous medium to effect classification of the material according to particle size, a return for oversize particles of material, and an outlet concentric with the cylinder and of less area than the space between the cylinder wall and the casing.

15. A classifier comprising a cylindrical casing, a cylinder having a smooth wall concentric with and spaced from the casing, a rotatable shaft on which the cylinder is mounted, means for rotating the shaft, means for feeding a suspension of material and a gaseous medium into one end of the space between the cylinder and the casing, the smooth wall cylinder being operated at such speed as to act upon the material and gaseous medium to effect classification of the material according to particle size, a return for oversize particles of material, a discharge outlet from the casing, and a plate extending at least partially across the space between the cylinder wall and the casing and located between that space and the discharge outlet.

16. A classifier comprising a cylindrical casing, a cylinder having a smooth wall concentric with and spaced from the casing, a rotatable shaft on which the cylinder is mounted, means for rotating the shaft, means for feeding a suspension of material and a gaseous medium into one end of the space between the cylinder and the casing, the smooth wall cylinder being operated at such speed as to act upon the material and gaseous medium to effect classification of the material according to particle size, a return for oversize particles of material, and a ring-shaped plate extending from the casing inwardly to a position adjacent the cylinder but spaced therefrom, the cylinder extending into the opening of said plate.

17. A classifier comprising a cylindrical casing, a cylinder having a smooth wall concentric with and spaced from the casing, a rotatable shaft on which the cylinder is mounted, means for rotating the shaft, means for feeding a suspension of material and a gaseous medium into one end of the space between the cylinder and the casing, the smooth wall cylinder acting upon the material and gaseous medium to effect classification of the material according to particle size, a return for oversize particles of material, a ring-shaped plate occupying a position between the casing and the cylinder but spaced therefrom, a discharge casing communicating with the last mentioned space and having a discharge outlet, and a fan mounted in the discharge casing.

HENRY G. LYKKEN.
